TO ALLIS-CHALMERS MANUFACTURING COMPANY, A CORPORATION OF DELAWARE.

TUBE-MILL.

1,120,343.

Specification of Letters Patent. Patented Dec. 8, 1914.

Application filed June 9, 1910. Serial No. 566,083.

To all whom it may concern:

Be it known that I, CHARLES F. SPAULDING, a citizen of the United States, residing at Denver, in the county of Denver and 5 State of Colorado, have invented a certain new and useful Improvement in Tube-Mills, of which the following is a specification.

This invention relates to improvements in the construction of tube mills, and relates 10 particularly to tube mills adapted to be used for a plurality of purposes and for grinding various amounts and grades of material.

An object of the invention is to provide a 15 tube mill having a plurality of chambers one or more of which are adapted to perform a grinding function, as in the ordinary tube mill, while the remaining chamber or chambers are adapted to be used as ore amalgamating or pulp thickening chambers, 20 or merely as a dead end of the mill.

Another object is to provide a means for 25 adjusting the length of the chambers, thus avoiding excessive wear on the linings of the grinding chamber at the discharge end thereof, which excessive wear results from 30 improper proportioning of the length of the mill to suit the character of the material being ground or from an improper amount of material being passed through the mill.

Still another object is to provide a mill in 35 which ore may be ground in the initial chamber of the mill, being passed on directly to an amalgamating chamber formed adjacent to the grinding chamber, the operations of grinding and amalgamating being 40 performed in the same mill. This latter object would make the mill especially adapted to be used in the milling of gold ores with the following advantageous results:

The stamp mills now universally in use could be replaced by rolls for coarse crushing followed by a tube mill for fine grinding, thus reducing the cost of installation; 45 the final grinding obtained would be better, that is to say, the substance would be ground finer, thus permitting better extraction of the values contained in the ore; the capacity of the installation would be increased, since 50 the rolls and tube mill would be idle only a short time while removing the valuables, during which time the plates containing the amalgam are being replaced by fresh plates, whereas with a stamp mill the entire mill 55 must be shut down while the amalgam is

being removed from the amalgam retaining surfaces; and, the dangers of pilfering and wasting of the amalgam would be avoided by having the amalgam and ore thoroughly mixed in a closed receptacle.

A clear conception of one embodiment of the invention can be obtained by referring to the accompanying drawing in which like reference characters designate the same or similar parts in like or different views.

Figure 1 is a fragmentary, part sectional view of a tube mill having an amalgamating chamber formed in one end thereof. Fig. 2 is a transverse vertical section of the device shown in Fig. 1, the section being taken on the line II-II of Fig. 1 looking in the direction of the arrows. Fig. 3 is a view similar to that shown in Fig. 2, showing a modification of the arrangement of the copper plates in the amalgamating chamber.

The tube mill consists essentially of a tubular metal shell 1 having end heads 31 formed in either end thereof. The interior of the shell 1 is lined with a plurality of lining or wearing plates 6 which may be of any desirable construction and which are generally removably attached to the shell 1. The end heads 31 may also be lined with plates made of suitable wearing material. Manholes 12, 18, of which there are a number along the body of the mill, permit of easy access to the interior of the mill for inspection or for the removal of working elements therefrom.

The driving gear 2 is fastened to the end 90 head 31 at the feed end of the mill and serves to rotate the mill during grinding. The feed trunnion 4 is mounted in a spherical bearing above the support 5 and is fastened to the feed end head 31. The feed 95 scoop or pump 3 is fastened to the outer overhanging end of the feed trunnion 4. The discharge trunnion 15 is mounted in a spherical bearing above the support 16 and is fastened to the discharge end head 31.

The partition 9 which is fastened to the lining plates 6 of the mill by means of a series of bolts 30, is shiftable or adjustable along the length of the mill and divides the mill into two chambers. There may be 105 a number of these partitions 9, depending upon the number of chambers desired and the purpose for which the chamber is to be used. The bolts 30 have their heads coacting in slots or grooves 21 formed between 110

adjacent ends of the plates 6 and project radially inward toward the center of the shell 1, passing through the cylindrical projecting flange formed on the outer edge of the partition 9. The partition 9 can therefore be moved to any position along the mill by loosening the nuts at the ends of the bolts 30 and removing the calking or filling strips which normally fill the grooves 21. The 10 grinding chamber side of the partition 9 is protected by hard iron or other wearing material plates 8. The discharge screen 7 is fastened to the partition 9 over the discharge opening formed through the center 15 of the partition 9, and coacts against the inner ends of the plates 8.

As shown, the interior of the portion of the shell 1 surrounding the amalgamating chamber at the discharge end of the tube mill is also lined by plates 6, the ends of which are spaced apart by slots or grooves 21. The baffle plate 13, which may be made of copper or similar amalgam retaining material, is spaced from the partition 9 by 25 spacers 10. The bolts 11 which pass through the plate 13, spacers 10, partition 9, and flange of the screen 7, serve to keep these elements in coaction. The copper or amalgam retaining plates 14, see Figs. 1 and 2, 30 are mounted on, but are spaced from the interior surface of the amalgamating chamber. These plates 14 are mounted on brackets 25 by means of bolts 17 or similar means permitting easy removal of the plates 14 from 35 the brackets 25. The brackets 25 are adjustably mounted on the liner plates 6 by means of bolts 19 which coact in the slots or grooves 21 formed between the adjacent ends of the plates 6. By loosening the nuts at the 40 inwardly projecting ends of the bolts 19, the brackets 25 can be shifted to any desirable position along the mill.

The discharge trunnion 15 could also be provided with a discharge screen 7, such as 45 is shown applied to the partition 9, but this is not essential. Drain plugs 20, one or more for each chamber of the mill, form a means for permitting the withdrawal of the liquid which during normal operation of 50 the mill fills both the grinding and amalgamating chambers to a level approximately at the central axis of the shell 1.

In the modification, see Fig. 3, the copper or amalgam retaining plates 22, instead of 55 being approximately parallel to the plates 6, are mounted perpendicular thereto, being radial to the shell 1. The brackets 23 are mounted in the grooves 21 formed between adjacent plates 6 by means of bolts 60 24, and are adjustable along the length of the mill. The plates 22 are again removably mounted in the brackets 23 to permit their easy withdrawal from the mill.

During the operation of the mill for mill- 65 ing gold ores, the ore after having been re-

duced in a stamp mill or rolls to a fineness desirable for tube mills, is admitted by means of the pump 3 through the feed trunnion 4 to the grinding chamber at the feed end of the mill. The rotation of the mill by 70 means of the gear 2, causes the ore within the mill to be continually intermixed with and reduced by the pebbles in the grinding chamber until the finely ground ore is eventually discharged from the grinding chamber through the screen 7 to the amalgamating chamber. Upon passing into the amalgamating chamber, the course of the material is deflected by the baffle plate 13, which plate causes the entering crushed ore to 75 travel toward the amalgam retaining plates 14 at the periphery of the amalgamating chamber. Mercury, which previous to starting has been admitted to the amalgamating chamber by means of a long spoon or similar means extended into the discharge trunnion 15, fills the lower portion of the amalgamating chamber. The gold-bearing, finely crushed ore upon being deflected by the plate 13 into the path of the constantly 80 agitated and flowing mercury, is mixed therewith and has its gold withdrawn, due to the affinity of the mercury for the gold. The combination of gold and mercury then strikes the plates 14 which are made of copper or other amalgam retaining material, and is deposited on the surfaces thereof in 85 layers. From time to time the mill is stopped and the plates 14 removed through the manholes 18, the stoppage of the mill 90 being only for such a length of time as will permit the removal of the amalgam coated and insertion of a new set of plates 14. If the baffle plate 13 is also used as an amalgam retaining means, it should be made sectional 95 or of a sufficiently small size to permit its removal through a manhole 18. The plates 13, 14, after removal from the mill are scraped, the valuables being thus removed 100 therefrom, after which they are again 110 ready for insertion in the mill. The residual or refuse remaining after the gold has been extracted from the ore, is eventually discharged through the discharge trunnion 15.

It may be here noted that the action of the plates 22 of the modification, upon the ground ore, see Fig. 3, would be slightly different from that of the plates 14. The plates 22, due to their radial positioning, would tend to carry the mercury above the center of the mill in the direction of rotation of the mill, from which position the mercury would be dropped or precipitated across the center of the amalgamating chamber, thus possibly producing a more 120 efficient mixing of the mercury with the gold containing ore.

If for any reason it is found desirable to either shorten or lengthen the grinding chamber, the partition 9 can be easily shift- 125 130

ed as heretofore explained. This shifting of the partition may be desirable for various reasons. It may be desirable to change the tonnage or capacity of the mill, thus requiring a change in length of grinding chamber. It may also be desirable to operate the mill on a different grade of ore, thus giving another possible cause for the shifting of the partition 9. Then again it 10 may be desirable to introduce more amalgam retaining surface or longer plates 14, giving still another possible cause for shifting the partition 9. These are only a few of the more important reasons why a shifting of 15 the partition 9 might be desired and many minor reasons will appear to one skilled in the art. The lengthening of the plates 14 would require the lengthening of the distance between the brackets 25, therefore requiring the adjustability of these brackets. It is, however, not necessary to have this adjustment of the partition 9 and brackets 25, performed in the manner herein shown and described, as a simpler method of attaining the same results could be devised. The amalgam retaining plates 14 could, moreover, be used direct as a lining for the amalgamating chamber instead of having them exposed on all sides, and might also 30 be placed projecting at an angle which is intermediate the radial and circumferential positions as disclosed.

Stamp mills which are now in universal use for the purpose of milling gold ore, do 35 not reduce the ore to a desirable degree of fineness prior to the amalgamation. The mills are, moreover, expensive and the floor space occupied by such an installation is very great. In applying the present invention for milling gold ores, the rough grinding can be done with a set of rolls, while the finer grinding is done in the tube mill grinding chamber. Such an installation would give much better grinding of the ore prior 40 to amalgamation and would decrease the cost and the floor space occupied by the mill for the same or even a larger sized installation. The advantages obtained by having the amalgam in an inclosed chamber are 45 also numerous, this feature tending to prevent pilfering and waste of the mercury, as well as permitting a better and longer contact of the amalgam with the retaining plates 14 than is at present obtainable with 50 the ordinary apron plates of the stamp mills.

It should be understood that it is not desired to be limited to the exact details of

construction shown and described, for obvious modifications will occur to a person skilled in the art.

It is claimed and desired to secure by Letters Patent,—

1. In a tube mill, a shell, trunnions on said shell, means for rotating said shell, a partition in said shell dividing same into a plurality of chambers, means of communication from one of said chambers to another, and means for adjusting the partition to change the lengths of said chambers. 60 70

2. In a tube mill, a shell, end heads co-acting with said shell to form an inclosed receptacle, a partition mounted within said shell and dividing the same into a plurality of chambers, one of said chambers being a tube mill chamber for pebbles, means of communication from one of said chambers to another, and a copper plate mounted within another of said chambers which is 75 free of pebbles. 80

3. In a tube mill, an inclosed shell, means for feeding ore to said shell, an outlet for discharging ore from said shell, said shell being divided into a plurality of chambers intermediate said feeding means and said outlet, one of said chambers constituting a tube mill grinding chamber, and another of said chambers constituting an amalgamating chamber, a removable copper plate mounted in said amalgamating chamber and spaced 90 from the walls thereof, and restricted central means of communication from one of said chambers to another. 85

4. In a tube mill, a shell, end heads co-acting with said shell to form an inclosed receptacle, a partition in said shell dividing the same into a plurality of chambers, means of communication from one of said chambers to another, and means for adjusting said partition to change the lengths of said 95 100 chambers.

5. In a tube mill, a shell, end heads co-acting with said shell to form an inclosed receptacle, a partition in said shell dividing the same into a plurality of chambers, constricted central means of communication from one of said chambers to another through said partition, and means for adjusting said partition to change the relative 105 110 lengths of said chambers.

In testimony whereof, I affix my signature in the presence of two witnesses.

CHARLES F. SPAULDING.
